UNITED STATES PATENT OFFICE.

LEO CANDA, OF CINCINNATI, OHIO.

DESIGN FOR A PICTURE-EXHIBITING CABINET.

SPECIFICATION forming part of Design No. 32,335, dated March 18, 1900.

Application filed February 10, 1900. Serial No. 4,825. Term of patent 3½ years.

To all whom it may concern:

Be it known that I, LEO CANDA, a citizen of the United States, and a resident of Cincinnati, Hamilton county, State of Ohio, have invented and produced a certain new and original Design for a Picture-Exhibiting Cabinet; and I do declare that the following is a description sufficiently clear, full, and exact to enable others skilled in the art to which the invention appertains to make and use the same, attention being called to the accompanying drawing, with the reference-numerals marked thereon, which form also a part of this specification.

The subject of this invention relates to a cabinet which is provided with view-openings through which pictures may be seen which are exhibited within.

The object is to increase the usefulness as well as to improve the appearance of such a cabinet by certain proportions of sizes and arrangement, shape, and configuration of parts and outlines thereof, all as hereinafter described, and illustrated in the accompanying drawing, which shows in a perspective view such a cabinet embodying my design.

The cabinet consists, substantially, of two box-shaped parts 1 and 2, one above the other and of equal breadth and depth, which latter, however, exceeds the former in each. They

are divided by a horizontal cornice or molding 3, the part 1 below which is higher than the part 2 above it.

Part 1 is provided with a socle or plinth 4, below which there are legs 5, upon which the structure rests. The sides of this lower part are paneled, as shown at 6.

The upper part 2, which rises above cornice 3, is considerably lower than the part below and contains the characteristic feature of my design, which consists of having the upper part 7 of the front inclined rearwardly and meeting with its upper edge the front edge of top 8. This upper part is suitably paneled, some of the panels, especially those in the sides, being of translucent material, and the inclined part of its front contains two view-openings 9, surrounded by an outwardly-projecting curved shield 10.

Having described my invention, I claim the same, as follows:

The design for a picture-exhibiting cabinet, substantially as shown and described.

In testimony whereof I hereunto set my hand in the presence of two witnesses.

LEO CANDA.
